BROACHING MACHINE

Julian L. Perkins and Hiram D. Croft, Springfield, Mass., assignors to Perkins Machine & Gear Company, Springfield, Mass., a corporation of Massachusetts

Application January 21, 1928, Serial No. 248,325

25 Claims.

(Cl. 90—8)

This invention is concerned with metal cutting machines and has for its general object the provision of a broaching machine adaptable to effecting the precision finishing of metal parts by open broach cutting operations at a high rate of production.

Another object of our invention is the provision of a broaching machine incorporating mechanical features directed to the precision indexing of the metal cutting tools comprising the broaches.

A further object of our invention is to associate with a broaching machine, mechanisms for automatically effecting precision indexing of the work or metal parts being cut whereby a plurality of precision cuts may be effected automatically upon the work.

A further object of our invention is to incorporate in a broaching machine of the character above referred to a mechanism for effecting the precision indexing of the work about more than one axis.

A still further object of our invention is to effect the automatic release of the work from the presented position of the work to the cutting tools after a predetermined number of operations upon the work has been effected by said tools.

A still further object of our invention is to coordinate in a broaching machine mechanisms which will effect the automatic presentation of the work to be cut by the broaching tools to the tool path.

A still further object of our invention is to provide a broaching machine which will automatically engage or grip work to be cut by the broaching tools in precision relation to one prefinished surface thereof.

A still further object of our invention is to coordinate in a broaching machine the foregoing referred to mechanisms in such manner that their functioning or cycles of operations will be controlled in a predetermined manner relative to reciprocating cycles of operations of the broaching tools.

A still further object is to arrange the said coordinated mechanisms in such manner that extraordinarily heavy cuts by the broaching tools upon the work blanks may be effected without the reactive stresses caused thereby interfering with the precision finishing of the surfaces being cut by the tools.

A still further object of our invention is the provision of an automatically operated broaching machine which is adaptable to the simultaneous cutting of a plurality of pieces of work.

55 Further objects of our invention will herein-

after become apparent from the following description of a broaching machine illustrated in the drawings to embody the various features of our invention. The essential characteristics thereof are summarized in the claims.

Our invention is concerned with improvements and further developments of the class of broaching machines known as open broaches; that is, the cutting action is effected by the reciprocating movement of a series of cutting teeth which are caused to act upon the work, the work being interposed in the reciprocating path of movement of the cutting teeth. Such a machine is generally disclosed in our prior issued Patent No. 1,409,766 and, as in that patent, the present invention is illustrated as being embodied in a machine for effecting the cutting of gear teeth, but it will be understood by those skilled in the art that the machine to be hereinafter described in detail is adaptable to precision finishing or cutting of a variety of pieces of work heretofore finished or cut by milling operations.

In the present instance, we incorporate in the embodiment of our invention duplex mechanisms which may be alternately operated in coordination with a pair of mechanically attached or connected reciprocating slides supported on the machine frame in an upright, counterbalanced relation, whereby the power required for reciprocating the slides and the broaching tools supported and carried thereby is reduced to only that necessary to overcome frictional resistance in the operation of the slides and tools and the reactive resistances of the work when being cut by the tools carried by the slides. To enhance the productive capacity of such a mechanism, we provide on each of the slides two broaching tools, each tool comprising an oscillatable bar having mounted thereon a row or set of rough cutters and a row or set of finishing cutters, the rough cutters being effective in doing the major cutting upon the work during reciprocation of the slide in one direction. The bars are oscillated on the completion of this roughing cut whereby the sets of finishing cutters carried thereby are brought into the cutting path, and a light finishing cut is effected over the previously effected rough cut, upon the return movement of the slide. An oscillatable broaching bar and attendant mechanism for its proper functioning is described and claimed in the Perkins, et al. Patent No. 1,486,604 issued March 11, 1924.

In the drawings, Fig. 1 is a plan view of a duplex broaching machine, embodying the features of our invention and for purposes of illus-

tration is shown as being particularly adaptable to effecting the broaching of gear teeth and work blanks; Fig. 2 is an enlarged front elevation of one of the mechanisms incorporated in the machine for presenting work to the cutting path of the broaching tools of the machine, and for indexing the work relative to the tool path; Fig. 3 is a front elevational view of a work handling fixture or mechanism which is a duplicate of the mechanism illustrated in Fig. 2; Fig. 4 is an enlarged fragmentary elevation of the work handling fixture or mechanism disclosed in Fig. 2; Fig. 5 is a fragmentary side elevation of the lower part of the mechanism illustrated in Fig. 2; Fig. 6 is a fragmentary side elevation of the mechanisms illustrated in Figs. 2 and 5, but with the mechanical elements thereof disposed in a different operative position than the positions of the same elements shown in Fig. 5; Fig. 7 is an enlarged cross sectional detail of a tool stroke control comprising part of the mechanism shown in Fig. 5 and taken along the line 7—7 of Fig. 5; Fig. 8 is a cross sectional detail of other parts of said mechanism and taken along the line 8—8 of Fig. 5; Fig. 9 is a cross sectional detail of a revolving support for work indexing mechanisms and taken along the line 9—9 of Fig. 4; Fig. 10 is a cross sectional detail of a precisioning plunger taken along the line 10—10 of Fig. 9; Fig. 11 is an enlarged side elevation of a duplex work indexing head adapted to be removably mounted upon the revolving support shown in Fig. 9; Fig. 12 is a cross sectional assembly view of the duplex work indexing head taken along a plane defined by the line 12—12 of Fig. 11; Fig. 13 is a plan view, bottom side up, of a precisioning couple comprising one of the important elements of the work indexing mechanism illustrated in Figs. 11 and 12; Figs. 14 to 17 inclusive are detailed views of parts of elements comprising the work indexing mechanism illustrated in cross section in Fig. 12; Fig. 18 is a fragmentary detail or side view of part of one of the broaching cutters; Fig. 19 is a cross sectional view taken through Fig. 12 along the line 19—19 of Fig. 12; Figs. 20 to 25 inclusive are detailed illustrations of other parts comprising the duplex work indexing mechanism illustrated in Fig. 12; Fig. 26 is an enlarged cross sectional view taken longitudinally through the top portions of oscillatable bars or arbors which support broaching tools such as is illustrated in Fig. 18, this section being taken along either of the lines 26—26 of Fig. 1; Figs. 27 and 28 are two views of a precisioning means incorporated in the mechanism illustrated in Fig. 26; Figs. 29 and 30 are diagrammatic representations of the oscillated positions on the broaching tools; Figs. 31 to 37 inclusive are detailed illustrations of other elements incorporated in the mechanism illustrated in cross section in Fig. 26; Fig. 38 is an enlarged fragmentary side elevational view of one of the oscillatable bars or arbors for carrying the broaching tools; Fig. 39 is a cross section taken through one of the arbors or broach supporting bars along the line 39—39 of Fig. 38 and showing the manner of clamping the cutters thereto; Fig. 40 is a side elevation of a modified form of mechanism illustrated in Fig. 6 whereby the mechanism illustrated in Fig. 6 may be operated automatically to cause the work indexing mechanism to present new work to the cutting paths of the broaching tools; Fig. 41 is a cross sectional fragmentary view of the mechanism shown in Fig. 40, taken along the line 41—41 of Fig. 40; Fig. 42

is a cross sectional detail of a revoluble indexing element incorporated in the mechanism illustrated in Figs. 40 and 41; Fig. 43 illustrates a modified form of mechanism for actuating the work indexing mechanism to cause the work to be indexed while remaining in position to be cut; Figs. 44, 45, and 46 are detailed views of elements comprising said modified form of indexing mechanism shown in Fig. 43; Fig. 47 is a cross sectional detail of a modified form of means for attaching interchangeable work engaging members to the indexing mechanism illustrated in cross section in Fig. 12; Figs. 48 and 49 are cross sectional details taken through the modified form of work engaging means shown in Fig. 47 and corresponding to the lines 48—48 and 49—49 respectively.

The illustrated embodiment of our invention comprises a broaching machine which has incorporated therein duplex features for greatly increasing the productive capacity of a pair of alternately reciprocal main slides, each of which may carry two broaching arbors or bars, and each bar has a set of finishing and a set of roughing cutters thereon for cutting bevel gear teeth. We accordingly provide in the present embodiment of our invention two groups of work indexing and supporting mechanisms which present the gear blanks to, and support the blanks in a position to be cut by the four sets of roughing cutters and the four sets of finishing cutters. These mechanisms are of such character, as will be hereinafter apparent, that the work can be indexed on the completion of each single cycle of reciprocations of each slide and the tools carried thereby, and then upon the completion of a predetermined number of roughing and finishing cuts and indexings of the work, the indexing mechanisms may be automatically swung away from the cutting paths of the tools thereby carrying the completed work with them, and this same movement is effective in causing a second set of work supporting and work indexing mechanisms to present new work or uncut work to the path of movement of the cutting tools, these actions being brought about at predetermined periods in the reciprocating movements of the slides and the tools carried thereby.

In the drawings, we show in Fig. 1 a machine frame 60 designed to support a pair of reciprocating slides 61 in vertical position, these slides engaging upright slideways 62 rigidly supported by the machine frame in spaced apart relation whereby an actuating pinion 63 may engage racks 64 secured to the opposite side faces of the slides 61, the pinion 63 being mounted upon a shaft not shown, and the shaft being driven through a suitable reduction gearing disposed within the portion 65 of the frame by a reversing motor 66. It will be understood, of course, that any suitable power reversing means may be utilized for driving the pinion 63 to alternately effect vertical reciprocation of the slides 61.

Mounted upon the top of the machine frame are sprockets 68 over which extends a stretch of chain 69, the respective ends of which are attached to the top ends of the slides 61, whereby the slide weights are counterbalanced. No further description or illustration of the slide design and actuation therefor is here given for a general mechanical arrangement for suitably mounting the slide to make it effective in supporting a broaching bar carrying two sets of cutting or broaching teeth is illustrated in the previously referred to Perkins, et al. Patent No. 1,486,604, 75

but the particular adaptation of the broaching bar illustrated in that patent to the present machine is modified to the extent that two broaching bars are mounted in cooperative pairs 5 on each slide, and a precisioning means therefor is incorporated in the present invention as will be hereinafter described.

In Figs. 38 and 39 we show the general structure of the bars supporting the tools, and these 10 bars comprise oscillatable members 70 of substantial weight and formed to receive and support a row of roughing cutters 72 and a row of finishing cutters 73 conforming in shape to a gear slot and angularly spaced apart 90°. The cutters are 15 mounted upon adjustable blocks 74 and 75 respectively, the blocks and cutters being maintained in position on the bars 70 by clamping members 78 which react against tapered sides formed on the cutters 72 and 73. Any suitable 20 means, such as screw members 79, may engage the clamping strips 78 and the bodies of the bars 70 to clamp in adjusted position. In Fig. 18 a side elevation of part of one of the cutters 73 is illustrated, the roughing cutters and the finishing 25 cutters being of substantially the same form.

The cutter carrying bars 70 are mounted on the slides in such manner that upon the downward stroke of the slide on which they are mounted the two sets of roughing cutters act on two 30 pieces of work positioned side by side, and upon the approach of the completion of the downward movement of the slide, the bars 70 are oscillated through 90° to shift the roughing cutters out of the cutting path and thus bringing the finishing 35 cutters into the cutting path before any substantial return or upward movement of the slide has taken place, and we show in Figs. 26 to 37 inclusive bar actuating means and precisioning means for bringing about this oscillating movement of 40 the bars upon the completion of the roughing or downward movement of the cutters, and also upon the completion of the finishing or upward movement of the cutters. This mechanism may comprise as shown in cross section in Fig. 26 a 45 pair of camming, indexing and precisioning plates 80 bolted together as shown at 81, to comprise a unitary member insofar as functioning is concerned, and these members are accurately machined to slidably fit upon reduced, upper extensions 70a of the oscillatable broaching bars 70. The under faces of the members 80 are provided with camming surfaces 80a in the form of slots disposed 90° apart and indexing or precisioning slots, coextensive with camming slots but having 55 more acute surfaces 80b. These two sets of slots coact with lugs on other members to be described to cause members 80 to be elevated against the influence of spring members 85 mounted to bear upon the members 80 in pre-compressed condition by reason of retainer nuts 86 threaded to the 60 uppermost ends of the extension 70a of the broaching bars 70, and also to cause members 80 to act as a precisioning means when the tools carried by the bars are cutting pieces of work. 65 Hence the elevation or disengagement of the members 80 may be effected by a pair of camming members 88 (see Figs. 26, 31, 32, and 33) coaxially mounted upon reduced portions 70c of the broaching bar 70. The members 88 are formed at 70 the bottoms thereof to have meshing spur gear sectors 88a, whereby they are caused to revolve in opposite directions when one of them is actuated, and as shown in Fig. 31, one of the members 88 is provided with an extension 88b to support a 75 stud 89, the stud carrying a roller 90 in such posi-

tion as to extend outwardly from a bearing block 91 which engages and supports the upper reduced portions 70c of the broaching bars. The rollers 90 are thus disposed outwardly to engage cam members 92 and 93 (see Figs. 34 and 35) respectively 5 disposed at upper and lower positions on the machine frame adjacent the path of movement of the slides to cause the members 88 to revolve in alternate directions upon each successive operation thereof by the respective cams. When the 10 members 88 are thus revolved, the indexing plate comprising the members 80 is caused to be raised by reason of the action of four camming lugs 88c which normally rest in the slots defined by the surfaces 80a (see Figs. 27 and 28), the angles 15 of these surfaces, however, being such that corresponding surfaces 80d formed on the lugs 88c (see Fig. 32) will cam the members 80 upwardly.

We provide a separate means in the mechanism shown in cross section in Fig. 26 which will be 20 acted upon by the members 88 to cause the broaching bars 70 to be oscillated or indexed only after the members 80 have been cammed upwardly by the members 88 in the manner just described, and this means may comprise, as shown 25 in Figs. 36 and 37, a pair of members 95 disposed within the interiors of the members 88 but precisely secured to tapered portions 70d formed on the upper ends of the broaching bars 70, and which are retained in place by nuts 96 in threaded engagement with the extensions 70a of the broaching bars. These members 95 are provided with radially extending lugs 95a, which are of less width than notches 88e (see Figs. 31 and 32) formed in the members 88, and in which the lugs 35 95a of the members 95 are disposed to swing. The members 95 are also provided with upwardly extending lugs 95b having surfaces complementary to the slots defined by the precisioning surfaces 80b formed in the under faces of the members 80. It will thus be seen that as the members 80 are revolved by reason of the stationary cams 92 and 93 upon the rollers 90, no movement of the members 95 will be effected and correspondingly no oscillating movement of the 40 broaching bars 70 will be effected, until the members 88 have cammed the indexing members 80 upwardly, thus disengaging these members from the lugs 95b on the members 95. A continuation of the revolving movement of the members 88 50 will then cause the bars to be oscillated through 90° in opposite directions as indicated diagrammatically in Figs. 29 and 30. It may be added that the bars 70 are suitably supported at their lower ends by bearing blocks attached to the 55 lower ends of the slides and which may correspond to the bearing blocks 91 illustrated in Fig. 26. It will be noted that the bearing block 91 is of heavy design to absorb any longitudinal reactions transferred thereto by the bars 70 during 60 the heavy roughing cut by the cutters on the work.

As previously stated we incorporate in the present machine duplex mechanism which may be alternately operated to present the work in 65 pairs to the pairs of broaching bars as the latter are alternately reciprocated by the slides 61, and each of these mechanisms may comprise two sets of work carrying and indexing mechanisms with automatic means for shiftably supporting 70 said mechanisms whereby one set may be active to support the work and index it, while the other set of indexing mechanisms is inactive and/or positioned so that the operator may remove the completed work and mount other uncut work up- 75

on the indexing mechanisms and the actuation of the various correlated mechanisms is effected by the reciprocating movements of the slides 61. Accordingly, in Figs. 2 and 3, two groups of mechanisms are represented in right and left-hand mechanical arrangement and each group incorporates the use of four sets of work indexing mechanisms. We will first describe the manner of mounting the indexing mechanisms on a revolving means for supporting them and will refer particularly to Figs. 2 to 9 inclusive and Fig. 11 of the drawings.

In Fig. 11, one pair of work indexing units is shown as detached from the machine and with a work blank (a bevel gear blank) mounted thereon. In Figs. 2 and 3, are shown in front elevation, triangularly shaped frame members 100 and 101, which, as shown in cross section in Fig. 9, revolvably support a frame member 102 made in the form of a hollow casting with pedestal pads or blocks 103 preferably integrally formed thereon, and upon which may be mounted casings 106 comprising the frames of the indexing mechanisms. This casing 106, as shown in cross section in Fig. 12, is of such form as to support two work indexing mechanisms and the triangularly shaped frame members 100 and 101 are pivotally mounted upon a rod or bar 104 supported by bearing brackets 105 resting on an adjustable slide frame carried by a front projecting portion of the machine frame 60, whereby the two frame members 100 and 101 may be oscillated in unison through linkage mechanism actuated by the slides 61 as the latter reciprocate. This linkage mechanism also includes the means for predetermining the number of broaching strokes upon the work before the work is withdrawn from the path of movement of the broaches and is arranged in duplicate at the two sides of the machine frame, but only one group of such members as comprise this mechanism will be described. The frame members 100 and 101 accordingly have the outer or lower front triangular ends thereof secured to cross member 108 and pivotally connected to the cross bar 108, are links 109, the lower ends of the links 109 being pivotally connected to bifurcated links 111 and 111a mounted upon a rocking shaft 112 suitably supported to extend through the frame member 110. The frame member 110 is adjustably mounted on the bed of the machine 110a by means of the tongue and groove 110b and adjustment screws 110c, whereby the work may be moved relative to the cutters and a fine adjustment is obtained. It will be noted that the links 109 and 111 constitute a toggle for swinging the triangularly shaped frame members 100 and 101 supported thereby about the axis of the rod 104, and this oscillating movement is effected only upon a predetermined number of reciprocations of the slide and the means for actuating this toggle mechanism at certain predetermined times will now be described.

Disposed at one side of the frame member 110 is a member 115 reciprocally supported by links or arms 116 and 117, the member 115 being reciprocated back and forth each time the broach carrying slide 61 makes one cycle of reciprocations. In other words, the link 116 is actuated by reason of the cam 116a mounted on the slide to engage a roller carried by the lever arm 118 and which is rigidly mounted on a stud shaft 119 to which the link 116 is secured, the stud shaft being supported in juxtaposition to the reciprocating movement of the slide and the cam car-

ried thereby, by bracket member 120. It will be noted that the link 117 is pivotally mounted on the bar 104 but is not directly effective in causing any movement of the frame members 100 and 101 mounted on the bar 104.

Associated with the reciprocating member 115 is a counting mechanism which functions in such manner that levers 136 and 148 indirectly transmit motion to the frame members 100 and 101, after a predetermined number of working cycles 10 of the cutting tool or broach. The links 109, 111 and 111a are thus caused to be aligned or to hinge toward each other and bring about the upward or downward swinging of the frame members 100 and 101 about the rod 104. As shown in Figs. 5, 6, and 7, the counting mechanism may comprise means controlling the positioning of the lever 136 whereby the latter becomes effective to cause the fixture to be swung from the position shown in Fig. 4 to the position shown in Fig. 6. This means includes an arm 120 oscillably supported by a stud 121 secured to a bracket member 122a attached to the side wall of the frame member 110. On the arm 120 is a downwardly extending portion 121a upon which is mounted a pawl 122, the latter being resiliently urged in contact with a ratchet wheel 124 also mounted on the stud 121, a spring 125 serving to act on the pawl. The ratchet wheel 124, as shown in Fig. 7, is mounted upon the stud 121 to be readily replaceable by other ratchets having a different number of teeth thereon for a reason which will hereinafter become apparent. The number of reciprocations which the main slide may make while the work is being maintained in position to be cut by the cutters mounted thereon is determined by the number of teeth in the ratchet, and accordingly the ratchet wheel is keyed to a disc 130, which acts on lever 136 through cam 135 rigidly mounted thereon. This disc member also serves as a friction brake by reason of the spring urged plunger 131 acting thereon to prevent any overtravel thereof, the plunger 131 being suitably supported by a bracket 132 attached to the frame member 110. It will thus be seen that each time the reciprocating member 115 makes one cycle of movements the ratchet and consequently the disc 130 is advanced through an angle corresponding to the angular span of one tooth in the ratchet, and when the disc is revolved to bring the cam member 135 to the position shown in Fig. 6, the cam will cause the lever 136 to be interpositioned in the oscillating path of the extension 111a of the link 117 to transmit motion from the lever 136 to the toggle linkage hereinbefore described. The lever 136 is mounted on a slidable bar 137, one end of which is slidably supported by a bracket 138 attached to the machine frame, while the other end is pivotally connected as indicated at 139 (see Figs. 5 and 6) to the toggle link member 111. Thus at a predetermined time or after a predetermined number of reciprocations of the main slides 61, the link 117 becomes effective to cause the toggle levers 109, 111 and 111a to be drawn from the extended position shown in Figs. 4 and 5 to a collapsed position as shown in Fig. 6, thus causing the frame members 100 and 101 to swing downwardly around the axis of the rod 104, and consequently causing the indexing mechanisms 10 carried by the frame member 102 to be swung away from the reciprocating path of movement of the broaching tools on the main slide 61, without arresting the continuous reciprocating movements of the main slide.

To prevent the reciprocating member 115 from further actuating the ratchet wheel 124, we provide a lever 140 on the stud 121 (see Figs. 5, 6, and 7), which has formed thereon a small cam 141, in such position as to pass between the pawl 122 and the ratchet teeth and thus raise the pawl out of engagement with the ratchet teeth as the frame members 100 and 101 are caused to be lowered as shown in Fig. 6. This we accomplish through a connecting rod 144 attached at one of its ends to the lever 140, and at the other end to an extension 111b formed on the top of the lever 111. It will thus be seen that the entire work supporting means will remain in the retracted position shown in Fig. 6 as long as desired, while the main slide continues to reciprocate.

To cause the fixture to be elevated to the position shown in Figs. 4 and 5, we arrange the dog lever 148 in pivotal attachment to the bar 137 whereby it may be elevated to have the end thereof become interpositioned in the path of movement of the end 117a of the link 117. As will be obvious, the link 117 is agitated or oscillated as long as the main slides of the machine are in operation. This dog lever 148 may be brought to operative position in any suitable manual manner, but we prefer to provide a means for raising the lever 148 whereby the latter can be set to be snapped into operative position regardless of the oscillating position of the end 117a of the lever 117. A device for accomplishing this may comprise a manually operated lever 150 (see Figs. 6 and 8) supported by a bracket 151 attached to a side wall of the frame member 110 in such position that a spring urged plunger member 152, carried by the hub portion of the lever 150, will engage the underside of the lever 148 when the lever 150 is shifted from the position shown in Fig. 6 toward the left and as the end 117a of the link 117 is oscillated to the extreme right, the plunger 152 will cause the lever 148 to snap upwardly and be interposed in the path of movement of the lever 117 as it swings from right to left, thus causing the toggle links to be shifted to lie in an upright position and consequently cause the indexing mechanisms and the work carried thereby to be swung to the path of movement of the cutting tools on the reciprocating slides. It will be noted that the foregoing described mechanisms for actuating the work carrying fixtures comprise members, some of which are constantly operated so long as the main slides are in operation while other of the members are acted upon by a timing mechanism which determines the period, measured in reciprocation cycles of the main slides, that the fixture is permitted to remain in elevated position with the work mounted interposed in the path of movement of the cutting tools carried by the slides, and we provide precisioning means which will assure accurate presentation of the work to such position, which will be hereinafter described.

Having described the means by which the work supporting and indexing mechanisms hereinbefore generally referred to are caused to be presented to the path of movement of the reciprocating cutters, we will now describe the manner by which these indexing mechanisms are swung on the fixtures and will thereafter describe the manner in which the indexing mechanisms index the work with precision, while the work is maintained in the path of movement of the cutters. In Figs. 4, 6, 9, and 10, disc members 160 are shown as being rigidly mounted upon

the revolving frame member 102, and upon which the indexing mechanisms are supported and the discs 160 have mounted thereon, in positions 180° apart, precisioning blocks or wedges 161 of such shape and disposed in such position that when the frame members 100 and 101 are swung about the bar 104, they will engage precisioning blocks 163 rigidly but adjustably supported by a thrust frame member 164 mounted on the machine frame at each side of each main slide. In other words, there are two frame members 164, two discs 160 and corresponding coacting precisioning wedges for each set of fixtures. The discs 160 also carry, at positions 180° apart thereon, precisioning sleeves 168 (see Figs. 4, 9, and 10) which are engaged by spring urged plungers 169, the latter being supported in a suitable bore formed in the triangularly-shaped frame members 100, and these plungers 169 are manually operated by a lever 170 when it is desired to manually revolve the disc members 160, and consequently the two pairs of indexing mechanisms carried thereby. The handle of the lever 170, as will be noted in Fig. 10, is provided with a lug 171 which will prevent any operation of the manual lever 150 when the plunger 169 is manually withdrawn from locking relation with the discs 160.

If desired, the discs 160 may be revolved automatically instead of manually at predetermined periods relative to the reciprocating movements of the main slides 61, and we show in Figs. 40, 41, and 42 a modified arrangement whereby this may be accomplished. Such mechanism may comprise a friction drive acting on a disc 190 having a beveled circumferential surface for friction drive and this friction drive being effected by a cone member 180, the cone being driven by a belt 181, and the belt being driven by a source of power application not shown. The cone 180 is mounted upon a sleeve 182 suitably supported by a bracket 183, the bracket 183 being mounted rigidly upon the frame member 110 in such position that as the frame members 100 and 101 cause the indexing mechanisms to be lowered about the pivotal axis of the rod 104, the beveled perimeter of the disc 190 will come into driven contact with the driving cone 180 and thus cause the member 102 and indexing mechanisms carried thereby to be revolved.

The frame members 160a of the indexing mechanism shown in the modification (Figs. 41, 42, and 43) are normally prevented from rotating relative to the carriage frame members 100 and 101, by suitable plungers 169a, one of which is shown in Fig. 41. The plunger shown is carried by the frame member 100, and the other, which is not shown, is carried in the same manner by the frame member 101. The plunger 169a engages a recess 168 in the indexing member 160 in much the same manner as did the plunger 169, heretofore described. In this modification, however, each plunger 169a is normally retained in engagement with its respective recess by a suitable compression spring 169b. The plunger 169a is preferably square or rectangular, and is mounted in similarly shaped recesses in the frame member 100.

As shown in Fig. 41, the plunger 169a has a downwardly extending bevelled nose 169c, which projects through a recess or slot in the frame member 100, and is positioned so that as the frame member 100 is rocked in a clockwise direction about its pivot 104, the bevelled nose of the plunger will engage a stationary bevelled lug 75

or cam member 191, which is rigidly secured to the stationary frame bracket 183. Accordingly, as the frame member 100 is rocked in a clockwise direction to move the work holding and indexing mechanism out of the path of the broach, the bevelled surface 169c of the movable plunger 169a is lowered into engagement with the stationary cam member 191. The continued clockwise movement of the frame member 100 causes the plunger 169a to be cammed outwardly by the stationary member 191, thereby causing the parts to be moved to the position shown in Fig. 41, in which position the plunger 169a is withdrawn from its coating recess 168.

15 Immediately before the locking plunger 169a is disengaged from the recess 168, a friction driving disk 180 is engaged by a disk 190, which is secured to the shaft 102 of the carriage. Hence, as soon as the plunger 169a disengages its recess 20 168, the work holder and indexing mechanism 25 will be automatically rotated by such friction drive.

20 In addition to automatically initiating the rotation of the index and workholding mechanisms, the mechanism is so arranged that it will be automatically stopped and locked in position. Likewise, the control lever 150 will be automatically reset to cause the frame members 100 and 101 to be rocked in a counter-clockwise direction 25 around their pivots, returning the work to a broaching position, as heretofore described.

25 To accomplish this, the rotation of the disk 160a is interrupted. As shown in Figs. 41 to 43, a cam disc 194 is secured to the disc 169a and its periphery is engaged by a roller 196, carried by a lever 197, pivotally mounted on the sleeve 182. The lever 197 is connected by a spring connection 197b to a second lever 197a, which is rigidly secured to the sleeve. Another lever 198 is rigidly secured to the sleeve 182, and is normally drawn in a clockwise direction by a suitable spring 198a, one end of which is secured to the lever 198 and the other end to the machine frame 110. This arrangement is such that the springs 198a and 197b serve to maintain the roller 196 in contact with the periphery of the cam disc 194.

30 In the embodiment shown, there are two work-holders and indexing mechanisms, K and L, which are diametrically opposed to each other, as shown in Fig. 4. The same is true of the modification shown in Figs. 41 to 43, inclusive. The machine is so arranged that the disc 160a will be stopped and locked in position after it has turned through half a revolution. To accomplish this the cam disc 194 is provided with two projecting peripheral surfaces 194a, spaced diametrically from each other, and arranged to act on the roller 196 to cause the levers 197, 197a and 198 to be rocked as a unit. The spring connection between the levers 197 and 197a is considerably stronger than the spring 198a which acts to retain the levers in their clockwise positions, hence, as the lever 196 is rocked, it moves the lever 198, which in turn, moves the lever 150 from the position shown in Fig. 4, to the position shown in Fig. 40. A link 258 is connected at one end to the lowermost end of the lever 198 and is provided with a pin and slot connection, 251—252, with the lever 150, below its pivot 253. Therefore, as the lever 198 is rocked in a counter-clockwise direction, the far end of the slot 252 will engage the pin 251, thereby moving the lever 150 to the position shown in Fig. 40. 35 This movement of the lever 150 raises the dog

lever 148 from the position shown in Fig. 5 to the position shown in Fig. 6, in which position it will be engaged by the lever 170a on the next rearward stroke. As the dog lever 148 is moved to the right, Fig. 5, it straightens the toggle 109, 111, rocking the frame members 100 and 101 to the broaching position shown in Fig. 4, and at the same time an ear 255 on the lower side of the dog lever 148 engages a plunger 152 (Fig. 5), heretofore described, returning the lever 150 to its normal position, as shown in Fig. 4, with the pin 251 (Fig. 40) riding idly in the slot 252.

40 As soon as the frame members 100 and 101 start to rock about their pivots, due to the action of a cam 194a, and the linkage 196, 197, 198, 15 and 148, as heretofore described, the plunger 169a, which is carried by the carriage, begins to move away from the stationary member 191, and is shoved by a spring 169b toward the face of the disc 168. As the disc is rotated by the friction drive, heretofore described, the plunger 169a will seat in a recess 168, stopping the rotation of the disc 160a and locking it in position relative to the frame members 100 and 101.

45 The friction drive is arranged through the medium of a spring 182a which urges the driving member 180 toward the driving disc 198 to maintain contact between the disc and the driving member 180, until after the plunger 169a is seated. It will be apparent that while we have described one means of automatically shifting the work to and from the path of the cutting tools after the completion of a predetermined number of cutting strokes of the reciprocating broaches, other means may be utilized for effecting the same, which we would consider to lie within the scope of our invention.

50 We will now describe the work indexing mechanisms and their mode of operation. As shown by the dot and dash lines in Fig. 4, one pair of 40 working indexing mechanisms K are in operative position with the two pieces of work W carried thereby disposed to lie in the cutting path of the reciprocating tools carried by the slides on the main frame of the machine. A second 45 pair of indexing mechanisms is shown in the same figure at L, and it will be noted from this figure that the ends of the fixtures to which the work W is attached, are disposed at an outward upwardly facing position whereby the operator may readily attach the work to the indexing mechanisms as the machine operates upon the work W carried by the indexing mechanisms K.

55 It will be noted in Fig. 4 that the indexing mechanisms K and L are mounted upon the revolving frame member 102 in such manner that when the indexing mechanisms are swung to bring the work W into the cutting path of the broaching tools, that the angular relation between the axes of the indexing mechanisms and 60 incidentally the gear blanks carried thereby and coaxially mounted thereon are brought into the desired exact angular relation to the vertical, whereby the broaching tools will accurately cut beveled gear teeth without necessitating any further finishing of the gear teeth, and when it is desired to cut beveled gears, the teeth of which have pitch angles different than the work blanks herein illustrated, the indexing mechanisms are mounted on the revolving frame at the desired 65 angle relative to the vertical.

70 As stated in the present instance, the work W (see also Figs. 11 and 12) comprises beveled gear blanks having a threaded bore, and accordingly the indexing mechanisms are provided with 75

removable studs 200 having threads 201 formed thereon to engage the threaded bore of the work, the gear blank having been previously machined whereby the back face is precise relative to the threads formed in the bore thereof. The studs 200 may be replaceably attached to a plunger member 202 comprising the central member or operating core of the indexing mechanism, and this plunger member is disposed within a revolvable, indexable sleeve 204, the sleeve 204 having flanges at its ends engaging bearing shoulders formed on the frame 106 which supports and houses the indexing mechanisms, a thrust ring 204a being interposed at one flanged end. The sleeve or sleeves 204 have mechanisms acting thereon to cause the sleeves to be revolved and thus effect the indexing of the gear blanks through angles corresponding to the number of teeth to be cut in the work blank. The sleeve 204 is accordingly also a reaction member for the action that clamps the work blanks and, as shown in Figs. 12 and 21, has an internal thread formed therein to engage a second sleeve 205 upon the upper ends of which are mounted spreader fingers 206. The spreader fingers have the short lever ends 207 thereof disposed to act upon a collar 208 in threaded engagement with the upper end of the plunger 202, the plunger 202 being formed in such manner as to provide for the disposition of a spring 209 whereby the latter may react between the inner end of the sleeve 205 and a shoulder formed on the plunger 202 to normally urge the plunger outwardly or downwardly as viewed in Fig. 12. The spreader fingers 206 may be spread by a pneumatically actuated spreader cone in the form of a piston 210 disposed within a floating cylinder 211, the latter having depending arms 212 which support blocks 213 in engagement with a pair of collars 214 and 215 on the plunger 202 whereby no relative movement between the cylinder member 211 and the indexing plunger 202 can take place. Thus, when the operator places a piece of work W in threaded engagement with the stud 201, he may control pressure within the cylinder 211 through a fluid conduit line 214 whereby the cylinder 211 and plunger 202 will go through a preliminary shifting or tensioning upwardly to cause the back face of the work blank W to engage the lowermost flange (Fig. 12) of the sleeve 204 firmly, and the accumulation of pressure within the cylinder 211 will thereafter cause the spreader cone or piston 210 to be forced downwardly against the influence of a spring 216, and consequently cause the fingers 206 to be spread and exert a further tensioning stress upon the plunger rod 202, thus firmly locking the work blank W in fixed relation to the indexing sleeve 204. When the pneumatic pressure is released by control valve (not shown) in the line 214 the spring 216 will cause the piston to shift upwardly thus releasing the tension on the plunger 202.

The manner in which the indexing sleeve 204 is indexed or partially revolved through the desired angular distance corresponding to the number of teeth being cut upon the work blank W will now be described. This indexing mechanism may also comprise a precisioning means corresponding in operation and function somewhat to the mechanism already described for effecting the oscillation and precisioning of the broaching bars 70, as shown in cross section in Fig. 26, the precisioning means being incorporated in the work indexing mechanism in modified form to meet the change of its environment. Briefly, the

sleeve 204 is locked in precision relation to a raisable member or pair of members 220 (see Figs. 12 and 13) which are bolted toge'her, the under sides of these members being provided with precisioning teeth or notches 221 (see Figs. 12 and 13), and these teeth or notches engage complementary teeth or notches 222 formed on ratchet members 223 (see Figs. 12 and 21) which are rigidly mounted upon the upper ends of the indexing sleeves 204, the ratchet portions 224 being engaged by pairs of pawls 225 mounted upon segment gear members 240, the members 240 being in mesh as shown in Figs. 12 and 15, whereby when one sleeve 204 of a pair of indexing mechanisms is indexed, the other will be indexed in an opposite direction. One of the members 223 is provided with a bevel or fan gear segment 226 (see Figs. 12 and 15) which is engaged by a fan gear 228 disposed within the frame 106 of the indexing mechanism and mounted upon a rock shaft 229 supported by the frame 205. Upon the outer end of the rock shaft 205 is mounted a lever 230. Thus, when the lever 230 is oscillated or rocked in a manner to be later described, the members 223 will be caused to oscillate, but the form thereof is such that a certain amount of oscillating movement will be permitted whereby the precisioning members 220 may be cammed upwardly against the influence of spring members 231, thus disengaging the notches or teeth 222, before any indexing of the work is effected. To this end, the members 240 have provided thereon upwardly extending cam surfaces 241 acting on cam rises 221a formed on the members 220, whereby the precisioning plates or members 220 will be caused to rise, as stated, before the pawls 225 engage the ratchet teeth 224 to bring about the indexing movement of the sleeves 204. A further movement of the fan gear 228 by the lever 230 thus causes the sleeve 204 and the plunger 202 to be indexed through the desired angle. It is accordingly apparent that the pistons may also follow this indexing movement but the cylinders do not. It will be noted here that the members 223 are removably mounted on the upper ends of the sleeves 204 whereby they may be replaced by other ratchet members having different numbers of teeth, depending upon the number of notches or teeth it is desired to cut in the work blank W, and that the precisioning members 220 are replaceable for the same reason.

The source of power for rocking the lever 230 comprises certain parts of the reciprocating movements of the main slides 61, but the lever 230 is positively operated in one direction only by a lug mounted on the main slides which carry the broaching bars (see Fig. 4). This lug may take the form of a dog 260 supported by a bracket 261 carried on the main slide 61 with a positive stop indicated at 262 controlling the movement of the member 260 in one direction and a spring urged plunger 263 supported by the bracket 261 to normally urge the lower end of the member 260 outwardly whereby, as the slide descends, the end of the lever 230 will be engaged during a certain amount of the movement of the main slide 61, and thereafter the lever 230, as it is swung downwardly, will become disengaged from the member 260. The lever 230 is then swung in an opposite direction by a plunger member 264 suitably mounted on the index frame 106 of the indexing mechanism, and is actuated by a spring 265 suitably positioned thereon. It will thus be seen that the ratchets, the fan gear 228 and the gear segments 240 are oscillated or revolved in one direction.

tion positively and returned to a normal position by the action of the spring 265 acting through the lever 230. Proper disposition of the actuating cam on the main slide relative to the cutter tools mounted thereon will cause the indexing of the work blank during such portion of the movements of the slide when the work is not being acted upon by the cutters.

In Figs. 43 to 46 inclusive we illustrate an alternate form of mechanism for imparting actuation to the indexing mechanism from the main slide as the slide reciprocates. This modified form of mechanism may comprise a pinion 270 mounted upon the rocker shaft 229, the pinion being actuated by a ratchet plunger 271, slidably mounted in a suitable slideway formed in the frame 106 of the indexing mechanism. The outer end of the ratchet member 271 is provided with a roller 272 which will be disposed within the descending and ascending paths of a cam member 273 adjustably mounted upon a bracket 274 attached to the main slide 61. As the slide 61 descends, the cam member 273 will cause the rack to revolve or oscillate the rocker shaft in one direction, and as it ascends, it will cause it to oscillate in the opposite direction upon each cycle or reciprocation of the main slides.

In Figs. 47 to 49 inclusive we show a modified form of interchangeable or replaceable means for engaging the work, and this means is illustrated in connection with the engagement of a gear blank "w". In this form of replaceable means, the work engaging stud 200 has the inner end thereof provided with a reduced portion 200b, the reduced portion being provided with a substantial head 200c with the sides thereof flattened as shown in Fig. 49, whereby this head may engage the slotted end of the plunger 202a in bayonet lock fashion, the reduced portion 200b being irregular in shape as shown in Fig. 48, whereby one diametrical dimension thereof will be greater than the width of the slot so that the removable member 200a is relatively non-rotatably engaged in the slot formed in the end of the plunger 202a. When it is desired to replace the plunger 200a with another plunger or similar work engaging member for engaging a different type of work blank than the gear blank shown, the indexing fixture is taken apart to a sufficient extent to permit the plunger 202a to extend out of the end of the sleeve 204, whereby the member 200a may be slipped out of engagement therewith. When the plunger is in its normally automatically operative position as shown in Fig. 47, the member 200a cannot be disengaged from the slotted end of the plunger 202a for the obvious reason that the indexing sleeve 204 would prevent any relative lateral shifting of the plunger 202a and the member 200a; that is, the sleeve maintains both of these members in alignment so long as the indexing fixture remains assembled as shown.

No valve means for controlling the air line 204 is shown but it will be apparent that such valve means can be incorporated in association with the pivotal mounting of the indexing fixtures whereby this valve action will become automatic when the fixtures are swung either manually or automatically by the fixture revolving mechanism shown in Fig. 41, or if desired, a manual valve means under the control of the operator may be provided.

It will be obvious to those skilled in the art that the main slides may be alternately reciprocated in the desired manner by any appropriate power transmitting means, such as alternately

operated clutches or by the well-known planer reversing belt drive, or by the use of a reversing motor, all of which do not enter into the disclosure of our present invention. A brief description of the operation of the entire machine will now be given.

When it is desired to effect the broaching of gear blanks of a certain pitch and number of teeth, the machine is first conditioned by placing thereon ratchet wheels 124 (see Figs. 5, 6, and 7) having a corresponding number of teeth, and ratchet members 224 are also assembled in the indexing mechanisms of the same number of teeth, as well as members 220 with a corresponding number of precisioning lugs or teeth. Roughing cutter and finishing cutter tools of the proper shape (according to pitch) are assembled upon the bars 70 and adjusted to the desired position for depth of cut, and the fixtures adjusted by an adjustment of their supporting tables relative to the slides and this may involve an adjustment of the precisioning block 163 on the frame members 164. The operator after various other incidental adjustments then mounts the work W upon the studs 201, which have been attached to the plungers 202, and by operation of a valve controlling the air line 214 (see Fig. 12) causes the blanks to be firmly engaged in position on the indexing mechanisms. The operator may then manually swing the fixtures to bring the gear blanks to an upper position and by manual operation of the lever 150 cause the toggle mechanism to be operated by the oscillating movement of the link 117, or if the automatic revolving feature disclosed in Figs. 40, 41, and 42 is incorporated in the machine, this swinging of the indexing mechanisms may be effected by simply starting the reciprocating movement of the main slides and at a predetermined time the work will be swung into cutting position. On the completion of each cycle of reciprocations, the four indexing mechanisms will function to index the work blanks through one gear tooth space until the predetermined number of teeth have been cut, whereupon the mechanism shown in Figs. 5, 6, and 7 will come into full operation, thus causing the indexing mechanisms to be first swung away from the cutting teeth of the reciprocating tools, and thence the indexing mechanism will be revolved to cause an interchange of their positions as shown in Fig. 4, and thereafter the entire operation of the machine is completely automatic excepting only the effort of the operator in placing upon and removing from the indexing mechanisms, the work blanks.

It will be readily understood by those skilled in the art that broaching operations of various forms may be effected on work pieces other than gears in which case the indexing fixtures may be replaced by automatic work clamping means adapted to the particular shape of the work. Thus while the tools are cutting pieces of work the operator may remove finished work and position other pieces to be cut without occasioning any interruption in the continuous operation of the machine.

We claim:

1. In a machine of the character described, the combination of a reciprocating slide carrying pairs of oscillatable broaching tools, means for effecting the oscillating movement of the tools at predetermined positions of the slide, a work-carrying fixture, means for causing the fixture to present a plurality of pieces of work carried thereby in precision relation to the reciprocating

path of said tools, and means connecting said pairs of broaching tools for maintaining said pairs of broaching tools in parallelism during the cutting action thereof upon said plurality of pieces of work carried by the fixture.

5. 2. In a machine of the character described, the combination of a pair of alternately reciprocating slides, roughing and finishing tools mounted on said slides in cooperative pairs, intermittently operated means for interlocking pairs of tools of corresponding function in parallelism, work-carrying and holding means for presenting work to the path of movement of said tools, and means for indexing the work while in said presented position.

3. In an open broach machine of the type described, the combination of a reciprocating broaching cutter, a supporting frame therefor, means for holding the work in precision relation 20 to the cutting path of said cutter and a precisioning means coacting with the last-named means for transferring the cutting thrust or reaction of the cutting tool upon the work to said supporting frame, whereby said reaction is taken by the frame in a direction substantially parallel to the reciprocating path of said tool.

4. In a gear cutting machine, the combination of a pair of reciprocating cutting tools, means for reciprocatingly supporting said tools whereby 30 they reciprocate in unison, means for presenting and holding gear blanks to be simultaneously operated upon by said tools, means for indexing said gear blanks in timed relation to the reciprocating movement of said tools, and an interconnecting means between said indexing means for accurately locating said gear blanks relative to each other and relative to the path of movement of said tools, said tools comprising oscillatable members, each carrying two sets of broaching 35 cutters, and means for oscillating these members in predetermined positions of the movement of the tools and the indexing movements of the gear blanks.

5. In a gear cutting machine, the combination of a pair of reciprocating cutting tools, means for reciprocatingly supporting said tools whereby they may reciprocate in unison, automatically operated means for presenting and holding gear blanks to be simultaneously operated upon by 50 each of said tools, means for indexing said gear blanks in timed relation to the reciprocating movement of said tools, and an interconnecting yoke between said indexing means for accurately locating said gear blanks relative to each other 55 and relative to the path of movement of said tools.

6. In a metal cutting machine having a metal cutting tool, the combination of an indexable spindle, and means to cause relative movement 60 between the tool and the spindle independent of the indexing movement of said spindle, means to secure work to said spindle, means to intermittently move said spindle to index the work, precisioning means to accurately position said spindle, said last-named means comprising a means secured to said spindle and coacting slideable means secured against rotary movement relative to the axis of said spindle, and means to slide the second-named means axially relative to the axis of the spindle and into and out of engagement with the first-named means.

7. In a metal cutting machine, the combination of an intermittently rotatable spindle, means securing work pieces to said spindle, precisioning means to accurately position the spindle, said

last-named means comprising a pair of members having coacting surfaces in a plane normal to the axis of the spindle, wherein one of said members is secured against rotary movement relative to said spindle and the other member is connected to rotate with the spindle, and wherein one of said members is arranged to move axially relative to the other member, both of said members being provided with interlocking jaw formations, equi-distant and radially spaced from each other, 10 the jaw formations on one member arranged to engage the jaw formations on the other member to accurately position the spindle radially, and means to cause axial movement of said axially movable member during a period of rest of said 15 spindle.

8. A metal cutting machine, a rotary element, a support therefor, means to secure work positioned on said element, means to intermittently rotate said element to index the work, precisioning means to accurately position the work after 20 each indexing movement, said precisioning means comprising a member drivingly connected to and in axial alignment with said element, a second member in axial alignment 25 with said element, said second-named member being slidably mounted relative to said first-named member and constrained against rotation, resilient means to cause such axial movement, each of said members having one face thereof 30 provided with a series of projections spaced apart from each other and from the axis of said element, the projections on each member forming a series of recesses into which the projections of the other member seat to accurately position the 35 work, and wherein the side walls of said projections form cam surfaces arranged to coact with similar cam surfaces on the other member to rotate the element to a predetermined position thereby accurately indexing the work.

9. In a metal cutting machine having a pair 40 of metal cutting tools, a fixture having a pair of workholding spindles arranged to retain work in position to be operated on by respective tools, said fixture comprising a frame, bearings in said 45 frame to support said spindles and maintain their axes parallel, means to impart rotary movement to said spindles to index the work pieces, precisioning means to accurately position the work and retain it stationary relative to the tool, 50 wherein said last-named means is supported directly on said spindles and is out of contact with the fixture frame and is connected to said frame only through the medium of said spindles.

10. In a metal cutting machine having a pair 55 of metal cutting tools, bearings for said tools whereby the axes of said tools are retained in parallelism, a fixture having a pair of workholding spindles, arranged to retain work in position to be operated on by respective tools, said fixture 60 comprising a frame, bearings in said frame to support said spindles and maintain their axes parallel, means to impart rotary movement to said spindle to index the work pieces, precisioning means to accurately position the work and 65 retain it stationary relative to the tool, said last-named means comprising independent means carried by and drivingly connected to rotate with respective spindles, and a common means to cooperate with both of said independent means and 70 supported by said spindles independent of the fixture frame.

11. In a metal cutting machine, a pair of metal cutting tool carriers, tool carrying bars rotatably mounted in said carriers, bearings for said tool 75

- bars and carriers whereby the axes of said tools are retained in parallelism, a fixture having a pair of workholding spindles arranged to retain work in position to be simultaneously operated on by respective tools, said fixture comprising a frame, bearings in said frame to support said spindles and maintain their axes parallel, means to impart rotary movement to said spindles to index the work pieces, precisioning means to accurately position the work, said last-named means comprising independent means carried by and drivingly connected to rotate with respective spindles, and a common means to cooperate with both of said independent means, said common means being slidably supported and restrained against rotary movement by said spindles independent of the fixture frame, and precisioning means for said spindles to accurately locate said tools, said last-named precisioning means being supported by said tool-carrying bars independently of said tool carriers.
12. In a metal cutting machine, the combination of a main frame, a reciprocating metal cutting tool, a work carrier in which work is revolvably mounted, a support in which said work carrier is revolvably mounted, a pivotal connection between said support and said frame, means acting consequent upon a predetermined number of strokes of said tool to rotate the work in the work holder, and independent means acting on a predetermined number of strokes of said cutting tool to swing said support about its pivot, and means released consequent upon the swinging of said support to restrain the relative movement between the workholder and the support.
13. In a metal cutting machine, the combination of a main frame having a pair of reciprocating tools mounted therein, a pair of independent carriers to rotatably support a work piece, a support in which said work carriers are rotatably mounted as a unit, a pivotal connection between said frame and said support, the axis of said pivot being parallel and offset from the axis of revolution of said work carriers, means acting consequent upon a predetermined number of strokes of the tool to swing the support about its axis, and means acting consequent upon a predetermined number of strokes of the tool to index the work about its axis independent of the swinging of the support.
14. In a metal cutting machine, a frame having a metal cutting tool mounted for reciprocation therein, a plurality of work carriers arranged to position work in the path of said tool, means carried by each work holder to rotate work held thereby relative to the respective workholder, said workholders being mounted for simultaneous revolution in a common support, a pivotal connection between said support and the frame, means to lock the workholders against rotation relative to the support, means to index the work in their respective workholders, means to swing said support about its pivot to move one workholder out of active position relative to the tool, means acting consequent upon the swinging of said support to automatically rotate said workholders relative to the support, and means acting consequent upon the rotation of said workholders to swing the support to position the work carried by another workholder in the path of the tool.
15. In a metal cutting machine, a main frame having a reciprocal metal cutting tool, a plurality of workholders to support individual pieces of work for individual rotation relative to said workholders, a support on which said workholders are

mounted for rotation as a unit, a pivotal connection between said frame and said support, means to rotate the work in the workholders, means to intermittently swing the support about its pivot, releasable means to prevent relative rotation between the workholders and the support, and means to release said releasable means consequent upon the swinging of the support relative to the frame.

16. In a metal cutting machine having a reciprocating cutter, a supporting frame therefor, a workholder, a frame for said workholder, a pivotal connection between the workholder frame and the tool supporting frame, means to swing the workholder frame about its pivot to position work carried by the workholder into the path of the cutter, a precisioning means to accurately locate the workholder frame relative to the main frame, and precisioning means including an abutment carried by one of said frames, means engaging said abutment carried by the other of said frames when the work is positioned in the cutting path of the tool, the coacting faces of the abutment and the engaging means being in a plane substantially normal to the cutting path of the cutter and located beyond the plane of engagement of the cutter with the work relative to direction of cutting travel of the cutter, whereby the cutting thrust or reaction of the cutting tool upon the work is transferred to the supporting frame substantially independent of the pivotal connection between the workholder frame and the cutter supporting frame and in a direction substantially parallel with the cutting path of the cutter.

17. In a metal cutting machine having a reciprocating cutter, a main frame, a workholder, a frame to support the workholder, a pivotal connection between the two frames, means to move one of the frames about its pivot to present work carried by the workholder to the cutting path of the cutter, means to accurately position the workholder frame relative to the main frame including interengaging surfaces on said frames arranged to coact with each other when the work is in the cutting path of the cutter, said surfaces being normal to the direction of the cutting travel of the cutter and located nearer the path of the cutter than the pivotal connection between the two frames to transfer the cutting thrust or reaction of the cutting tool upon the work to the tool supporting frame, whereby said reaction is taken by the tool supporting frame in a direction substantially parallel with the cutting path of the tool.

18. In a metal cutting machine, a main frame having a reciprocating metal cutting tool carried thereby, a workholder frame, a pivotal connection between the workholder frame and the main frame, a plurality of workholders rotatably mounted as a unit in the workholder frame, means to rock the workholders as a unit in the workholder frame to successively position work carried by respective workholders to be projected into the cutting path of the tool consequent upon the rocking of the workholder frame about its pivot, an abutment rigidly carried by one of said frames a seat carried by the main frame to coact with the abutment to accurately locate the workholder frame and transmit the cutting thrust of the tool on the work from the workholder frame to the main frame.

19. In a metal cutting machine, a main frame having a reciprocating metal cutting tool carried thereby, a carriage pivotally connected to the

main frame, a workholder frame rotatably mounted on the carriage, a plurality of workholders mounted on said workholder frame, means to rotate the workholder frame to position the workholders for presentation to the cutting path of the tool consequent upon the rocking of the carriage about its pivot, and means carried by the workholder frame to engage the main frame when the work is in the path of the cutting tool and transmit the cutting thrust directly from the workholder frame to the main frame, the surface of said means and the surface of the main frame engaged by said means being in a plane normal to the direction of travel of said tool.

20. In a metal cutting machine having a pair of reciprocating metal cutting tools, a frame, a carriage mounted on said frame to reciprocate as a unit with said tools, each of said tools being carried by spindles mounted for rotary movement in said carriage, means carried by and interconnecting said spindles to accurately position the tools relative to their rotation movement and lock them stationary relative to the carriage during the cutting action of said tools, a pair of workholders to present workpieces to respective tools, each workholder including a rotatable spindle, means interconnecting said last-named spindles to accurately position the work relative to their rotative movement and lock them against rotation during the cutting action of the tools.

21. In a metal cutting machine having a reciprocating metal cutting tool, common carriage reciprocable with said tool and in which the tool is rotatably mounted, means to intermittently rotate the tool to index it relative to work, means to accurately locate the indexed tool, said last-named means comprising a pair of members having coacting surfaces in a plane normal to the axis of the tool, wherein one of said members is secured against rotary movement and the other member is connected to rotate with the tool and one of said members is arranged to move axially relative to the other member, both of said members being provided with interlocking jaw formations equi-distant and radially spaced from each other, the jaw formation on one member being adapted to move the other member about its axis consequent upon relative axial movement between the members and thereby radially position the tool.

22. In a metal cutting machine, a workholder comprising a frame, a sleeve rotatably journaled in said frame and constrained against axial movement, a member slidably mounted for axial movement in said sleeve, work supporting

means carried by one end of said member and projecting beyond the end of said sleeve, means acting on said member to slide it axially relative to said sleeve to bring work carried by said member into contact with said sleeve, means to retain the work in contact with the sleeve, and means to turn the sleeve about its axis and thereby turn the work.

23. In a metal cutting machine, a workholder comprising a frame, a sleeve rotatably journaled in said frame and constrained against axial movement, a spindle slidably mounted for axial movement in said sleeve, work gripping means carried by one end of said spindle and projecting beyond the end of said sleeve to slide said spindle axially relative to said sleeve to bring work carried by said spindle into contact with the end face of said sleeve, and indexing means to turn the sleeve about its axis and thereby index the work.

24. In a metal cutting machine, a workholder comprising a frame, a sleeve rotatably journaled in said frame, a member slidably mounted for axial movement in said sleeve, work supporting means carried by one end of said member, a pair of spreader fingers carried by said sleeve and coacting with said member to move it axially relative to said sleeve, means to spread said fingers whereby the axial movement of said member brings work carried by said member into contact with said sleeve to lock the work and the sleeve for rotation as a unit, and means to rotate said sleeve.

25. In a metal cutting machine, a workholder comprising a frame, a sleeve rotatably journaled in said frame and constrained against axial movement, a member slidably mounted for axial movement in said sleeve, work gripping means carried by one end of said member and extending beyond the end of said sleeve, a pair of spreader fingers pivotally carried by said sleeve, each of said fingers having a surface coacting with said member, whereby the spreading of said fingers moves said member axially in one direction, resilient means to move said member axially in the other direction, wherein the axial movement of said member causes the work carried thereby to be brought into and out of binding contact with said sleeve, means carried by said member to spread said fingers, operating means for said last-named means, means to intermittently turn said sleeve about its axis, and means to accurately locate said sleeve and lock it against turning following each turning movement, and means to release said last-named means.
